CLAIM

The ornamental design for an espresso tamper holder as shown and described.

DESCRIPTION

FIG. 1 is a front, right, and top perspective view of an espresso tamper holder, showing my new design;

FIG. 2 is a front, right, and top perspective view thereof;

FIG. 3 is a rear, left, and bottom perspective view thereof;

FIG. 4 is a front view thereof;

FIG. 5 is a rear view thereof;

FIG. 6 is a left side elevation view thereof;

FIG. 7 is a right side elevation view thereof;

FIG. 8 is a top plan view thereof;

FIG. 9 is a bottom plan view thereof; and,

FIG. 10 is an enlarged view of an circled area labeled "10" in FIG. 1.

The broken lines depict portions of the espresso tamper holder that form no part of the claimed design.

The dot-dash broken lines in FIGS. 1 and 10, framing portions of the claimed design show enlarged portions of the espresso tamper holder and form no part of the claimed design.

1 Claim, 10 Drawing Sheets
